DESIGN FOR A COLOGNE BOTTLE

Wesley R. Hauptman, Los Angeles, Calif., assignor to Nassour Bros., Inc., Ltd., Los Angeles, Calif., a corporation of California

Application January 21, 1942, Serial No. 105,351

Term of patent 14 years

(Cl. D58—8)

To all whom it may concern:

Be it known that I, Wesley R. Hauptman, a citizen of the United States, residing at Los Angeles, in the county of Los Angeles and State of California, have invented a new, original, and ornamental Design for Cologne Bottles, of which the following is a specification, reference being had to the accompanying drawing, forming a part thereof, and in which:

Fig. 1 is a front elevational view of the cologne bottle showing my new design.

Fig. 2 is a rear elevational view of the bottle shown in Fig. 1.

Fig. 3 is a plan view of the bottle shown in Figs. 1 and 2.

Fig. 4 is a view of the bottle in side elevation.

I claim:

The ornamental design for a cologne bottle, as shown.

WESLEY R. HAUPTMAN.
